(57) **CLAIM**

We claim the ornamental design for a camera module, as shown and described.

DESCRIPTION

FIG. 1 is a front perspective view of a camera module showing our new design;

FIG. 2 is a rear perspective view of the camera module of FIG. 1;

FIG. 3 is a front elevational view of the camera module of FIG. 1;

FIG. 4 is a rear elevational view of the camera module of FIG. 1;

FIG. 5 is a left side elevational view of the camera module of FIG. 1;

FIG. 6 is a right side elevational view of the camera module of FIG. 1;

FIG. 7 is a top plan view of the camera module of FIG. 1; and, FIG. 8 is a bottom plan view of the camera module of FIG. 1. The broken lines depict portions of a camera module in which the design is embodied and form no part of the claimed design.
